UNITED STATES PATENT OFFICE.

JOHN R. DEIHM, OF POTTSVILLE, PENNSYLVANIA.

SPRING BED-BOTTOM.

SPECIFICATION forming part of Letters Patent No. 320,765, dated June 23, 1885.

Application filed December 5, 1884. (No model.)

To all whom it may concern:

Be it known that I, JOHN R. DEIHM, of 5
Pottsville, in the county of Schuylkill and
State of Pennsylvania, have invented a new
and Improved Spring Bed-Bottom, of which
the following is a full, clear, and exact description.

This invention relates to the construction of
the bed-bottom itself, and to means whereby
10 the bottom may be tightened up, the same being
adapted to be applied to the frame of the
bed, thus avoiding the use of a separate frame
for holding the bed-bottom.

Reference is to be had to the accompanying
15 drawings, forming part of this specification,
in which similar letters of reference indicate
corresponding parts in both the figures.

Figure 1 is a broken plan view of my invention
applied to an ordinary bedstead; and
20 Fig. 2 is a sectional elevation of the same,
taken on the line *xx* of Fig. 1.

The bedstead A, consisting of the side
pieces, *a*, foot-board *b*, and head-board *c*, may
25 be of the usual or of any approved construction.
The spring-bottom B is composed of the coiled wires *d* and link-plates *e*, to which
the wires are fastened, the plates *e* each being
formed with four holes, *e'*, for that purpose.
The plates *e* are secured together by the short
30 wires links *f*, that are fastened in the central
slots, *f'*, made in the plates *e*, as shown clearly
in Fig. 1, thus permitting the plates *e* to have
slight lateral movement without strain upon
the coiled wires *d*. Formed with or attached
35 to the coiled wires *d* are the straight wires *d'*,
by which the end coiled wires, *d*, in the bottom
are fastened to the stretching-rollers *C*, by
which the bottom may be tightened up. These
rollers *C* are by preference made tubular, and
40 are each formed with the series of holes *g*,
through which the wires *d'* pass. They are
each provided at one or both ends (preferably
at both) with a ratchet-wheel, *h*, with which
the pawls *i*, pivoted to the inner surfaces of
45 the side pieces, *a*, of the bedstead, are adapted
to engage, for holding the rollers *C* from turning
back when the bed-bottom is tightened by
turning the rollers.

For securing the tubes or rollers *C* to the

side boards, *a a*, of the bedstead, I employ the 50
open journal or bearing plates *C'*, so that the
tubes *C* may be put in place in the bedstead
and removed without taking down the bed-
stead. The plates *C'* are each formed with a
bearing or journal, *j*, and the edge of the plates 55
is cut away down to the bearing *j*, as shown
at *j'*, forming an entrance to the bearing *j* of
sufficient size to admit the ends of the tubes
C, and by preference the plates *C'* are recessed,
as shown at *k*, to receive and inclose the 60
ratchet-wheels *h*; but this may be omitted if
the ratchets *h* are made of the same or less
diameter as the tubes *C*, and the plates *C'* are
secured to the inner surfaces of the side pieces,
a, by screws *l*, so that my invention may be applied 65
to any bedstead. When the tubes *C* are
put into the bearings *C'*, and the wire bottom
attached to them by the straight wires *d'*, the
bottom may be tightened up by simply turning
one or both of the tubes *C* by means of a 70
wrench, or otherwise, and in case the bottom
becomes slack by use it may be easily tightened,
and the bottom may be made very tight
or somewhat slack, as desired by the user; and
by means of open bearing or journals, that 75
hold the rollers *C*, no difficulty will be experienced
in taking down or setting up the bed, and in addition to these advantages the bed is
practical, cheap, durable, and very convenient,
and may be applied to any bed without the 80
use of a separate frame.

Without the straight wires *d* the bottom
could not well be tightened up, as above set
forth; hence this forms an important part of
my invention.

Having thus described my invention, what
I claim as new, and desire to secure by Letters
Patent, is—

The bottom B, composed of slotted plates
e, coiled and straight wires *d d'*, and connect- 90
ing-links *f*, in combination with the rollers *C*,
for tightening up the bottom, substantially as
described.

JOHN R. DEIHM.
